UNITED STATES PATENT OFFICE.

GEORGE R. COTTRELL, OF TOTTENVILLE, NEW YORK.

GARBAGE-INCINERATING APPARATUS.

No. 839,270.

Specification of Letters Patent.

Patented Dec. 25, 1906.

Application filed March 30, 1904. Serial No. 200,754.

To all whom it may concern:

Be it known that I, GEORGE R. COTTRELL, a citizen of the United States, residing at Tottenville, in the county of Richmond and State of New York, have invented certain new and useful Improvements in Garbage-
Incinerating Apparatus, of which the following is a specification.

This invention relates to furnaces for incinerating garbage and refuse, destroying the noxious vapors and odors arising therefrom, and utilizing the gas and other valuable by-products.

The object of my invention is to provide for effectively treating garbage and refuse in divided portions or charges on separate grates one above another in my improved furnace, for readily dumping each charge when at the proper stage of treatment to the grate below, and agitating the garbage to prevent it from becoming impacted until it is completely incinerated.

In the effort heretofore made to burn garbage on grates or shelves one above another the garbage would remain moist, sticky, and impacted against the furnace-wall, adhering to the latter, so that the grate could not be rotated for dumping its charge without much loss of time and waste of heat.

By my improved construction and operation these difficulties are overcome and improved results secured.

I inject jets of combustible gas or hydro-carbon vapor and currents of hot air around the circumferential edges of the grate or wall of the furnace, producing circles of flame adjacent to the furnace-walls, so that the circumferential edges of the different layers or charges of garbage on the grates are first dried and burned away, thus permitting the grates to be readily rotated and the charge dumped to the grate below. I am thus enabled to keep the charges agitated and loose, so as to be readily permeated by currents of hot air and flame, thereby greatly facilitating the drying and incinerating operations.

The walls of the incinerating-chamber are made flaring from the ash-pit to the top like an inverted cone, so that the largest grate area will be at the top, where the fresh moist garbage may be spread out in the thinnest layer to facilitate drying. As the charges become dried and reduced by incineration they are dumped onto grates of successively smaller area, where combustion and reduction proceed more and more rapidly till the incin-

eration is completed. By this construction the furnace may be worked to its full capacity and all heat units utilized, resulting in a great saving of fuel.

Another object of my invention is to provide for storing garbage in tight hoppers or other suitable receptacles on a wharf, collecting the same by means of a boat containing the incinerating apparatus and as the garbage is discharged from the hopper squeezing out the water, then assorting it by hand to remove and separately store tin cans, metal, glass, rubber, &c., and at the same time exhaust all odorous gases into the furnace, so as to insure satisfactory sanitary conditions. In this operation an air-tight flexible hood is stretched over the squeezing-rollers and conveying-belt, so that the odor shall not escape, and an exhaust-fan is used for drawing the odorous vapors into the escape-flue of the furnace. By gathering the garbage and treating it on a boat, as can be done in many large cities, the long and expensive haul or transportation by land is avoided and decidedly economical results secured. The length of time required for storage and treatment of the garbage is also much shortened, and thus danger arising from long exposure of the garbage to fermentation is overcome.

Another object of my invention is to provide for condensing or concentrating the odorous vapors and particles of ash and carbon drawn off from the incinerating-furnace and utilizing the same as liquid fertilizer; also, to provide for treating the uncondensed gases to convert them into illuminating-gas, and thus utilize all the valuable by-products. The grease and tarry matter are also drawn off from the condensing-tank for separate treatment. In my process and apparatus the garbage and refuse are subjected to incinerating, distilling, and condensing operations, so that all noxious vapors are destroyed and the sanitary conditions made perfect.

The matter constituting my invention herein will be set forth in the claims.

I will now describe the details of construction and operation of my improved incinerating-furnace and condensing apparatus by reference to the accompanying drawings, in which—

Figure 1 represents a vertical longitudinal sectional view of the garbage and refuse furnaces and part of the condensing apparatus. Fig. 2 represents a vertical sectional eleva-

tion of the remainder of the apparatus. Fig. 3 represents a transverse section through the garbage-furnace on line 3 3, Fig. 1, and through part of a boat and a conveyer-belt, 5 also the garbage-hopper in elevation. Fig. 4 represents a horizontal section, on enlarged scale, through the garbage-furnace on line 4 4, Fig. 1. Fig. 5 represents a horizontal section, on enlarged scale, through the burner 10 flue for gases on line 5 5, Fig. 2. Fig. 6 represents a perspective view of part of a hollow perforated grate and the arbor for turning the same. Fig. 7 represents a detail 15 view of the grate-operating lever and ratchet-wheel. Fig. 8 represents detail views of the journal-box and shield. Fig. 9 represents a detail view of the grate and operating-gearing. Fig. 10 represents a detail view of an 20 oil-spray pipe. Fig. 11 represents a longitudinal section of a boat, showing my apparatus thereon.

The garbage-furnace A and refuse-furnace A' are constructed with incinerating-chambers B and B', containing the garbage-supporting grates, and with ash-pits X, having doors x. These furnaces are connected at the top by the large steam and vapor escape flue D, which connect by a downtake-flue D' with the condensing-tank G. The walls of 30 the furnaces A and A' are constructed of brick, and both of them are preferably provided with water-jacket linings a. A water-inlet pipe a', Fig. 3, connects with the lower end of the jacket a, and a steam-outlet pipe a'' connects with the top thereof for conducting the steam off to any desired place of use. The furnaces are preferably made circular in cross-section, and the furnace A particularly is constructed with the walls flaring upward 35 and outward from the ash-pit to the top in the form of an inverted cone or frustum for giving a large grate area at the top and gradually-decreasing area toward the ash-pit. This shape best accommodates the large 40 quantity of garbage or refuse which is supplied at the mouth or top of the chamber, permitting the same to be spread into a comparatively thin layer on the top grate, so that it may be readily evaporated, dried, and prepared for dumping to the grate below. The 45 inner wall of the furnace A' connects by an inclined portion b with the top of the furnace A, so as to form an acute angle at the junction of the two furnaces and prevent lodgment of the refuse material at that point.

A series of transversely-disposed grates E are suitably journaled in the incinerating-chambers B and B', so that they may be readily vibrated and revolved for dumping 50 the charge from one grate to the other. I preferably use three grates in the garbage-furnace B and two in the refuse-chamber B', as shown in Fig. 1. The grates are composed of hollow perforated bars open at their outer 55 ends for supplying air to support combus-

tion, both of the garbage and of the injected combustible gas or vapor. The grates are, preferably, constructed of upper and lower cast-iron sections, which are bolted together, as shown in Fig. 6, forming the main central hollow bar e and the lateral bars e', which latter gradually increase in length from the ends toward the center, so as to fill the cross-area of the chamber, as indicated in Figs. 1 and 4. The bars e' are preferably perforated only at 75 their under surfaces, as shown in Figs. 3 and 6, and they may be square in cross-section when the upper and lower halves are joined together. The center bar e has a square opening for receiving the square end of the arbor e'', as shown in Fig. 6, for convenience in vibrating or revolving the grate. Each grate may be conveniently placed in position or removed by means of a hollow detachable arbor e'', which also serves as a journal at opposite ends of the grate, as shown in Figs. 1, 6, and 9. These arbors or journals are supported in boxes b', fitted in the walls of the chambers, as shown in Figs. 1 and 8. The journal-boxes are also shown on enlarged 90 scale in Fig. 8. By means of this construction a grate can be readily removed and replaced by a new one when desired. The arbors e'' are open at their outer ends outside of the walls of the furnace and are preferably 95 connected at one side of the furnace with the air-supply pipes C, having valves c, as shown in Fig. 1. The arbors e'', Fig. 9, at the opposite ends of the center bars e project through journal-boxes and are provided at 100 their outer ends with lever-handles e'', ratchet-wheels e'', and spring-pawl d'', as shown in Figs. 1 and 7, for vibrating or revolving the grates. Instead of a lever-handle I may apply a beveled pinion to the outer 105 end of the arbors and provide a beveled gear meshing with said pinion and suitable shafting for vibrating and revolving the grate.

In the walls of the furnace and between the grates, or above the same, are placed a 110 series of tangentially arranged or inclined gas-jet burners f, connecting by branch pipes having valves f' with the main supply-pipe F for gas or hydrocarbon vapor, as shown in Figs. 1 and 4. The burner pipes or nozzles 115 are inclined to the circumferential wall, as shown in Fig. 4, so that the gas-flames are discharged in the form of a circle, which circulates adjacent to the inner wall in position to most effectively act upon the circumferential edges of the layers of garbage upon the grates, burning the same and preventing the charge from becoming impacted against the furnace-walls. Air is supplied to the injected gas or hydrocarbon vapor through the 120 grate-bars for effecting perfect combustion of the fuel. Evidently air may be supplied with the gas through the injector-burners in a 125 well-known manner.

Since the walls of the incinerating-cham- 130

bers B B' will become very highly heated by the circles of flame, which would be destructive to brick, causing partial fusion thereof and adhesion of ash and carbon, I provide iron water-jackets *a* for such chambers. The charge of garbage therefore as dumped from one grate to the other will slide freely down the inclined wall to the grate below. The burner-pipes *f* are preferably passed through openings *f'''*, as shown in Fig. 8. The journal-boxes *b'* are preferably made of cast metal in upper and lower halves and provided with extension-plates containing the openings *f'''*. Inclined shields *b''* are secured to the inner ends of the journal-boxes for protecting the journals and preventing ashes or refuse from entering the boxes, as shown on enlarged scale in Figs. 8 and 9.

The gas and vapor flue *D* is preferably made large and secured to the top of the furnaces A A', as shown in Figs. 1 and 3, and are provided at the sides with openings *d'*, to which are fitted the sliding doors *x'*. Any suitable means may be used for fastening the doors tight upon their seats. The flue *D* is provided near the top with two or more circular openings *d*, fitted with short inlet-pipes containing the fans *T*, mounted upon stands *t*. The fans *T* may be operated by electric or other power and serve for drawing noxious gases or vapors from the spaces below the hood *U* and discharge them into the flue *D*. The flue *D* connects by the downtake-flue *D'* with a condensing-tank *G*, which is provided at the bottom with a drain-pipe *g'*, having a valve *g''*, as shown in Fig. 2. For the purpose of producing a strong exhaust-draft from the incinerating-furnaces I provide water-sprays discharging in the downtake-flue *D'*.

An endless-chain pump *H*, having suitable wheels and endless chains provided with buckets *g*, is suitably mounted above tank *G*, as shown in Fig. 1. Pipes *h h* are provided for the endless chains and buckets and are secured to the top plate of the tank. Perforated pipes *h'* connect with said pipes *h* and pass in a U shape down into the tank, so as to be submerged in a liquid, as shown in Fig. 1.

Discharge-pipes having perforated nozzles or rose-heads *h''* connect with the upper ends of the pipe *h* and deliver strong sprays or jets of water into the downtake-flue *D'*. These sprays of water produce a strong draft and also serve for condensing vapors and causing precipitation of all ash and carbon which are drawn off from the incinerating-furnaces. The liquor in tank *G* is pumped over and over again until it becomes highly charged with products of condensation, forming a liquid fertilizer. This is drawn off from time to time through the drain-pipe *g'*, and fresh water is supplied as required from any convenient source. The liquor in tank

G becomes highly heated to a boiling temperature, and the matter not condensed at such temperature is drawn off through a discharge-pipe *I*, which connects with the top of tank *G*, as shown in Fig. 2. Pipes *I' I''* form a continuation of pipe *I* and connect with the second condensing-tank *K*. The downtake-pipe *I''* may be supplied with some form of porous material to serve as a wet scrubber for the gases which are passed through it. The water-supply pipe *H''* passes down through the top of pipe *I''* and terminates in a rose-head *h'''* for supplying fresh water to condense and purify the gas.

In the pipe or flue *I*, I construct a centrifugal flame-burner which is composed of inclined burner-pipes *f'''*, connecting with the circular supply-pipe *F''*, as shown in Figs. 2 and 5, and of a flaring spreader and air-inlet *L*. An air-supply pipe *C'*, having a valve *c'*, connects with the lower end of the conical spreader *L*. Air is discharged from the upper flaring end of the cone *L* for causing combustion of noxious gases which pass up through the flue *I*.

The inclined burner-pipes *f'''* produce a solid centrifugal flame around the cone *L*, and the noxious gases which pass from tank *G* are caught by the circulating flame and consumed. The gaseous products which pass off from this burner are mostly fixed gases, and they may be passed off through the pipe *k'''* to the ash-pit of the furnaces A A' or to any other place of use. These gases may also be passed off through the pipe *k''* into return-pipes in the retort-furnace *M*. The pipe *k''* may be continued backward and forward through the furnace *M* and connect by a return-bend *m'* at the front with the oil-retort *m*. The gases are thus highly heated and prepared for enriching with hydrocarbon-oil vapors in the retort *m*.

Hydrocarbon oil is supplied from the pressure-tank *N* through the pipe *n*, which connects with a perforated pipe *n'*, Fig. 10, extending through the retort *m*. The gas is here carbureted and enriched and is then converted into fixed gas by passage through other pipes or retorts in the furnace *M* and finally escape through the discharge-pipe *m''* into the gas-holder *O*. This holder is provided with the usual water-tank *O'* and with an outlet-pipe *o* for conducting gas to any desired place of use. The gas may be used as a heating agent for steam-boilers or as a motive power in gas-engines. This apparatus for carbureting and fixing the waste gases is used in connection with the incinerating apparatus when it is located on land, but could also be used on a boat when desired.

A force-pump *N'* may be used for drawing oil from an underground tank to supply the pressure-tank *N*. A small air-pump *n''* is used for forcing air into tank *N* above the oil for forcing oil through pipe *n* to the retort.

The tank K is provided with an outlet-pipe *l*, having a valve *l'* at about the liquid-level for drawing off grease or tarry matter from the surface of the liquid. An overflow trap-pipe *j* connects with an opening at the bottom of tank K for drawing off water, and a drain-pipe *j'*, having a valve, is also provided for draining the tank when desired.

- A garbage-storage hopper or other suitable receptacle P is mounted upon the end of a wharf V, Figs. 3 and 11, and is provided with a tight-fitting cover *p* and a bottom discharge-spout *p''*. A sliding damper *p'* is fitted in the spout *p''* and is provided with a rack-bar *p'''*. This rack-bar is engaged by a pinion *q*, having a lever-handle *q'*, suitably mounted in a standard on the wharf. Upon the deck of a barge or scow are mounted the two squeezing-rollers R just below the discharge-spout *p''*, and such rollers are mounted in the sliding journal-boxes *r* in the frames *r''*. The openings for the boxes *r* are elongated and fitted with spiral springs *r'*, which bear upon the boxes, forcing them inward. The rollers are thus mounted in yielding spring journal-boxes, so as to accommodate irregular masses of garbage and still exert a strong pressure for squeezing water out of the moist material. On the deck of the boat, just below the rollers R, is supported a chute S', which is provided with a conveyer-belt S, passing over the rollers *s*, mounted on the standards *s'*. The conveyer-belt S is preferably perforated, so that liquid which is squeezed out by the rollers R will pass through the same onto the chute below and thence off through drain-pipe S², which passes around the furnaces and connects with the tank G, dipping down below the surface of the liquid therein, as shown in Fig. 1. A wide flange *u'* is riveted to the hopper P, and a canvas or other cover U overlaps the same and is connected by coiled springs *u* to the hopper and at its opposite edge is connected to the flue D of the furnaces. The space above the conveyer-belt and between the hopper and incinerating-furnace may thus be covered in while garbage is being discharged from the hopper P and supplied to the furnaces. All noxious vapors and odors are thus held in a confined space and are drawn by the exhaust-fan T and discharged into the flue D. This will thus be passed off with the vapors and gases from the furnaces and discharged by the water-sprays through the downtake-flue D' into the condensing-tank G. A large amount of water is squeezed out of moist garbage by the rollers R, thereby saving time and expense of evaporating the same in the incinerating-furnaces. The water thus squeezed out is added to that which is contained in tank G, making liquid fertilizer.

The chute S' inclines to the garbage-feed opening *d'* in flue D for conveniently supply-

ing the garbage to the top grate E in the incinerating-furnace. The sliding doors *x'* are provided with a chain or rope *t*, passing over a pulley *t'*, for raising and lowering the same. As the garbage is traversed forward on the conveyer-belt S it may be assorted by attendants, who will pick out pieces of iron, glass, rubber, &c., and throw them into separate bins J, J', and J². These materials are preferably saved and disposed of separately. The assorting can be readily performed as the garbage travels from the squeezing-roller to the furnaces.

My garbage and refuse incinerating furnaces may be operated continuously—that is, fed with garbage and refuse at the supply-opening and the ashes moved in a practically continuous manner until the garbage is exhausted, though it is not intended that the feeding-doors and ash-pit doors shall be continuously open. Ashes will be removed only when necessary. The garbage is discharged from the hopper P onto the squeezing-rollers R, which are revolved for squeezing out the water and discharging the garbage upon the conveyer-belt S. The garbage is assorted by attendants, who will remove pieces of iron, rubber, and glass, placing each material in a separate bin J, J', and J². The remaining combustible material is fed forward and discharged onto the top grate E, where it is spread in a comparatively thin layer. The gas or oil vapor being now ignited at the burners and air admitted to the hollow grate-bars, evaporation and drying takes place very rapidly by reason of the ascending flame. At suitable intervals the top grate is vibrated to agitate and loosen the charge until it is sufficiently reduced to be dumped, when the grate is rotated or turned into a vertical position and the charge dumped onto the grate below. Air will be supplied through the outer ends of the grate-bars to the jets of gas or vapor at the burner-nozzles f, causing circles of flame around the circumferential edges of the charge of garbage on each grate, causing it to be burned and permeated by the hot air and flame, so that the grate can be readily vibrated or revolved and the charge dumped when properly reduced. When each charge of garbage is dumped from a grate, it will readily fall apart on the grate below, exposing new surfaces to the flames issuing from the burners. In order to spread the charge, the grate is vibrated, so that the garbage will be agitated and spread over the entire surface of the grate. On the bottom grate the charge is completely incinerated, and the ashes will fall into the ash-pit X, from which they may be removed through the door *x* at suitable intervals. Evaporation having been commenced on the top grate, the pumps H are started and sprays of water discharged through the rose-heads *h''*, thereby drawing off the steam and vapors.

and condensing them in the tank G. During the exhausting operation particles of ash and carbon are drawn over through flue D and deposited in tank G. They are valuable additions to the liquid fertilizer which is made in said tanks. The endless pumps H are continued in operation, pumping the liquid over and over again until it becomes highly concentrated. At suitable intervals the valve g" is opened and a portion of liquid fertilizer is drawn off through pipe g' and stored in suitable receptacles. The highly-heated products discharged into the tank G will cause the liquid to be boiled therein, so that all volatile matter will be driven off and caused to pass through the combustion-flue I, where all noxious gases and offensive odors are completely burned and destroyed by the solid centrifugal flame circulating around the inverted cone L.

Air admitted through the cone L causes complete combustion of the gases. Practically fixed gases will be exhausted through the pipes I I' I" by the water-sprays h". The gas is washed and cleaned by this water-spray and may be drawn off from tank K and returned to the ash-pits of the incinerating-furnaces or may be passed through pipe k" through the retort-furnace M, where, it is heated and then discharged into the oil-retort m. The gas is here carbureted and enriched and is then fixed by passage through two additional retorts connected by the return-bend m' and is finally passed off through the pipe m" into the holder O.

The furnace A' is intended for burning refuse material which is comparatively dry and which does not require so large a grate-surface as the moist garbage which is evaporated and burned in the furnace A. The refuse-chamber B' will be fed from a separate chute or platform and may be used for burning sawdust, chips, shavings, and other combustible refuse matter.

By my method of collecting garbage and refuse with a boat, which may be done at the water-front of many large cities, the garbage and other refuse can be conveniently hauled a comparatively short distance and stored in hoppers or bins on wharves and discharged therefrom into the boat. When desired, a large quantity of garbage may be discharged at one time into a hopper or bin on the boat, which can then be propelled out on the river or bay, during which time the garbage may be treated as above described. The operation of treating the garbage can thus be actively conducted while the boat is passing from one wharf or station to another. The destruction of the garbage and gases is thus effected in the least offensive and objectionable manner. Sanitary conditions are thus perfectly maintained, and the work of treating the garbage is economically conducted.

It is to be noted that in my method all the

valuable by-products are saved and utilized, and no offensive odors are allowed to escape from the garbage-incinerating apparatus.

Having described my invention, what I claim as new, and desire to secure by Letters Patent, is—

1. A garbage-furnace comprising an incinerating-chamber, a series of hollow perforated grates therein having air-supply pipes and capable of being rotated, and a series of 75 burners arranged in the wall above each grate, substantially as described.

2. A garbage-furnace comprising an incinerating-chamber, a series of grates therein capable of being rotated, and having bars 80 open to the external air and open at their ends, adjacent to the burners, and a series of burners arranged in the wall above each grate for producing a circle of flame, for burning the circumferential edges of each 85 charge of garbage, for facilitating the dumping and incineration of the charge of garbage, substantially as described.

3. A garbage-furnace comprising an incinerating-chamber having flaring walls 90 from below upward, a series of grates therein capable of being rotated and of the largest area at the top and decreasing area toward the ash-pit, and a series of burners arranged in the wall above one or more grates, whereby 95 the fresh moist garbage may be spread in a thin layer at the top, and, as incineration proceeds, may be dumped onto the grates of gradually-decreasing area toward the bottom for better drying the garbage and utilizing all the heat units.

4. A garbage-furnace comprising an incinerating-chamber, a series of grates therein capable of being rotated, a series of inclined or tangentially-arranged burners arranged 105 in the walls above the grates, and means for supplying air at the outer edges of the grates and adjacent to the burners for burning the circumferential edges of the garbage on the grates and preventing it from becoming impacted, substantially as described.

5. In combination with a garbage-incinerating chamber, the garbage agitating and dumping grate composed of a hollow central bar and hollow perforated lateral bars, open 115 at their outer ends, a hollow adjustable arbor extending through the wall and connecting with one end of said central bar, means for rotating said arbor and grate, and an air-supply pipe connecting with the other end of 120 said bar, substantially as described.

6. A garbage-furnace comprising an incinerating-chamber, having a water-jacket lining, a series of grates therein capable of rotation and having hollow arbors and bars 125 communicating with the outer air, and a series of burners tangentially arranged above each grate.

7. The combination with a garbage-furnace, comprising an incinerating-chamber, 130

grates therein capable of rotation, gas or vapor burners and air-inlets adjacent thereto, of a vapor-escape flue leading from the top of the furnace, a connected condenser-tank and a water-spray device in said escape-flue for exhausting and condensing the vapors and gases, substantially as described.

8. The combination with a garbage-furnace, comprising an incinerating-chamber, a series of dumping-grates therein, a series of burners and means for supplying air between the grates, of an escape-flue leading from the top of the furnace, an exhaustor therein and a burner in the escape-flue for burning gases and destroying odors, substantially as described.

9. The combination with a garbage-incinerating furnace, of a vapor-escape flue, a connected condensing-tank, a water-spraying device in said escape-flue, a liquid-circulating device connected with the tank and with said spraying devices, an outlet-flue from said tank and a gas-burning device in said flue having injector-burners and an inverted conical spreader having a connected air-inlet pipe for burning noxious gases, substantially as described.

10. A garbage-furnace comprising an incinerating-chamber, a series of hollow revolute grates therein, each having an air-inlet and air-outlets adjacent to the wall of the chamber, and a series of burners in the wall adjacent to each grate, substantially as described.

11. A garbage-furnace comprising an incinerating-chamber of increasing area from below upward, a series of revolute grates therein of decreasing area from above downward and burners in the wall above one or more grates whereby the moist garbage may

be spread in a comparatively thin layer at the top and dumped from one grate to another for better drying and burning the same, substantially as described.

12. In combination with a garbage-incinerating chamber, an agitating and dumping grate composed of a hollow central bar and hollow lateral bars open at their outer ends, an arbor connecting with one end of said central bar and extending through the wall, means for rotating said arbor and grate, said central bar having an air-inlet, substantially as described.

13. The combination with a garbage-incinerating furnace and its vapor-escape flue, on a movable support, of a stationary garbage-storage hopper, a canvas or other covering yieldingly connected with said vapor-flue and storage-hopper and an exhaust-fan placed in an opening leading into the vapor-flue, substantially as described.

14. The combination with a garbage-incinerating furnace, and its vapor-escape flue, having an opening and an exhaust-fan connecting therewith, and located on a movable support, of a stationary garbage-hopper having a discharge-spout and damper, squeezing-rollers and a conveyer-belt below the same, and a canvas or other flexible covering adapted to connect with the escape-flue and said hopper for preventing the escape of vapors and odors, substantially as described.

In testimony whereof I have signed my name to this specification in presence of two witnesses.

GEORGE E. COTTRELL.
